PAPER MAKING MACHINE

Daniel Catchpole Bert, York, Pa.

Application December 11, 1934, Serial No. 757,055

3 Claims.

(Cl. 92—49)

This invention proposes divers improvements in paper making machines, one object of the invention being to provide an arrangement of pressure rolls, located about a suction drum, in such a compact fashion that the felts may be made much shorter than heretofore. A further object of the invention is to provide novel means whereby the pressure rolls exert a progressively-increasing pressure in the direction of the drum and act with progressively-decreasing resiliency upon the drum.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

25 In the accompanying drawings:

Fig. 1 is a diagrammatic representation of the device forming the subject matter of this application, associated with a paper making machine;

30 Fig. 2 is a vertical section showing portions of the device claimed, in operative relation to a suction roll, most portions being in elevation;

35 Fig. 3 is a transverse section taken through the part of the paper making machine wherein the present device has been incorporated, parts being broken away;

Fig. 4 is a vertical transverse sectional view showing, in elevation and in section, parts which cooperate with a suction roller.

The numeral 1 in Figs. 3 and 2 designate a 40 part of the frame of a paper making machine, the frame including arches 2 (Figs. 3 and 4). On one side portion of the frame 1, a standard 3 is mounted. A standard 4 is disposed opposite to the standard 3. A removable block 5, generally 45 made of aluminum, is interposed between the lower end of the standard 4 and the adjacent part of the frame 1. The block 5 is held to the adjacent part of the frame 1 by a dowel 6, or otherwise, and a key 7 connects the block 5 with the standard 4. The block 5 is made of aluminum, in order that it may be light, and removable readily by one man, to permit the felts (hereinafter referred to) to be assembled with the suction roll hereinafter described.

55 Caps 8 are superposed upon the standards 3 and

4, and form parts thereof, the caps being connected to the standards, detachably, as shown at 9. In the standards 3 and 4, and in the caps 8 are journaled tubular shafts 10, projecting outwardly from the end walls 11 of a suction drum 12 having perforations 14, the end walls 11 preferably being in contact with the inner surfaces of the standards 3 and 4, and the caps 8, to hold the drum 12 against movement in the direction of its axis. The drum 12 may be of any 10 desired construction and may be rotated by any suitable means, conventionally indicated by a gear 15 (Fig. 3) secured to one of the tubular drum shafts 10, and meshing with a pinion 16 (Fig. 2) on a shaft 17 journaled in the standard 15 5. The suction means for the drum 12 is marked by the numeral 32.

The arches 2 (Fig. 4) are supplied with openings 48, which are elongated circumferentially of the arches. Slides 49 are mounted for adjustment in the openings 48. The slides 49 can be adjusted in the openings 48 by means of screws 50, threaded into the arches 2 and engaging opposite sides of the slides 49, as Fig. 4 will show. Levers 51 and 52 are fulcrumed intermediate their ends at 53 on the lowermost slides 49, and are located at one side of the arches 2, as disclosed in Fig. 4. Screws 54 have their upper ends pivoted at 55 to the outer ends of the levers 51 and 52, and pass slidably through lugs 57 on 20 the arches 2. Hand wheels 56 are threaded on the lower ends of the screws 54, and, cooperating with the lugs 57, constitute means for raising the inner ends of the levers 51 and 52. Radius arms 58 and 59 are pivoted at 60 to the uppermost 25 slides 49. Lifting screws 61 have their lower ends pivoted to the inner ends of the arms 58 and 59, the screws 61 passing upwardly through the arches 2. Hand wheels 62 are threaded on the upper ends of the screws 31, and, cooperating 30 with the arches 2, constitute means whereby the radius arms 58 and 59 may be swung upwardly at their inner ends. Bell crank levers 64 are fulcrumed at 65 on the slides 49 which are located in the lower right hand portions of the arches 2 35 in Fig. 4. The bell crank levers 64 are operated by screws 66, journaled in the arches 2 and held against longitudinal movement therein, the screws 66 being provided at their inner ends with hand wheels 67. The screws 66 are threaded into ridges 68, whereonto the depending arms of the bell crank levers 64 are connected pivotally and for limited movement, as shown at 69.

Referring to Fig. 4, a first shaft 70 is journaled on the inner ends of the levers 51 and carries a 55

first pressure roll 71 cooperating with the drum 12. The first pressure roll 71 is of ordinary construction. A second shaft 72 is journaled on the inner ends of the levers 52 and carries a second pressure roll 73, cooperating with the drum 12. The second pressure roll 73 is made of highly resilient and soft material, such as rubber. A third shaft 74 is journaled on the inner ends of the radius arms 58. The third shaft 74 carries a third pressure roll 75, cooperating with the drum 12. The third pressure roll 75 is made of soft and resilient material, such as rubber, but is not so soft and resilient as the second pressure roll 73. A fourth shaft 76 is journaled in the inner ends of the radius arms 59 and carries a fourth pressure roll 77. The pressure roll 77 cooperates with the drum 12. The pressure roll 77 is made of soft and resilient material, but is not so soft and resilient as the third pressure roll 75. A fifth shaft 78 is journaled on the inner ends of the bell crank levers 64. The fifth shaft 78 carries a fifth pressure roll 79, cooperating with the drum 12. The fifth pressure roll 79 is of ordinary construction.

The first pressure roll 71 is located a little above the axis of rotation of the drum 12. The pressure rolls 73, 75, 77, and 79 are spaced apart circumferentially of the drum 12. The roll 79 is located a little above the axis of rotation of the drum 12.

The rolls 73, 75, and 77 are resilient, but they increase in hardness, in the order indicated. The rolls 73, 75, and 77 engage the drum 12 with progressively increasing pressures, because the shafts 72, 74, and 76 increase, in the order stated, in diameter or width, and therefore in weight. As a matter of fact, the progression as to pressure extends from the first pressure roll 71 to the fifth pressure roll 79.

In Fig. 1, the upper felt 80 receives the pulp from the cylinders 81, as usual, the couch rolls being shown at 82. The upper felt 80 passes around the pressure roll 71, between the pressure rolls 73, 75, and 77, on the one hand, and the drum 12 on the other hand, the upper felt being extended backwardly around the roll 79, and over idlers 83. The lower felt is marked by the numeral 84. It extends around idlers 85, and between the drum 12 on the one hand, and the upper felt 80 and the pressure rolls 71, 73, 75, 77, and 79, on the other hand.

Owing to the fact that the rolls 71, 73, 75, 77, and 79 are arranged in compact form about the periphery of the drum 12, at the place where the partially completed stock goes to the driers (not shown) the felts 84 and 80 may be made much shorter than is customary. Persons conversant with the paper industry will recognize the de-

sirability of making the felts 80 and 84 short, because the felts are expensive, and do not last very long. One of the advantages of the device forming the subject matter of this application is that it is economical in the use of felts.

In practical operation, the drum 12 is rotated by the gears 16, the pinion 16 and the shaft 17, or their equivalent. The upper felt 80 receives the pulp from the cylinders 81 and the pulp moves, along with the felts 84 and 80, part way around the periphery of the drum 12, under pressure exerted by the rolls 71, 73, 75, 77, and 79, the stock passing to the driers, (not shown) at the roll 79. Suction is created in the drum 12 through the means shown at 32 in Fig. 3. The moisture in the stock is squeezed out of it by the rolls 71—73—75—77—79, and the extraction of the moisture from the stock is promoted by reason of the fact that the rolls 73, 75 and 77 increase progressively in hardness, and by reason of the fact that these rolls are thrust down by a correspondingly increasing progressive pressure, as has been explained hereinbefore. The moisture passes through the perforations 14 of the drum 12 into the drum, the moisture passing out through the suction connection means shown at 32.

Having thus described the invention, what is claimed is:

1. In a paper making machine, a suction drum journaled for rotation, means for producing suction within the drum, pressure rolls, and means for supporting the pressure rolls about a portion of the periphery of the drum, for rotation, the pressure rolls being resilient and decreasing progressively in resiliency.

2. In a paper making machine, a drum journaled for rotation, means for producing suction within the drum, pressure rolls, shafts of different diameters supporting the pressure rolls about a portion of the periphery of the drum, for rotation, and constituting means for causing the pressure rolls to exert a progressively increasing pressure on the drum initially determined by the weights of the shafts, and means under the control of an operator for varying said initially determined pressure and still keeping the pressure progressive.

3. In a paper making machine, a drum journaled for rotation, means for producing suction within the drum, pressure rolls, and means for supporting the pressure rolls about a portion of the periphery of the drum, for rotation, the pressure rolls being resilient, and decreasing progressively in resiliency, the pressure rolls exerting a progressively increasing pressure on the drum.

DANIEL CATCHPOLE BERT.
